UNITED STATES PATENT OFFICE.

JACOB J. STORER AND FRANK MARTIN, OF HELENA, MONTANA, ASSIGNORS
TO THE UNITED MILL AND FURNACE COMPANY, OF MONTANA.

AMALGAMATOR.

SPECIFICATION forming part of Letters Patent No. 573,834, dated December 22, 1896.

Application filed September 12, 1893. Renewed April 11, 1896. Serial No. 587,232. (No model.)

To all whom it may concern:

Be it known that we, JACOB J. STORER and FRANK MARTIN, of Helena, county of Lewis and Clarke, State of Montana, have invented 5 certain new and useful Improvements in Amalgamators, of which the following is a full, clear, and exact description, reference being had to the accompanying drawings, and to the numerals of reference marked thereon.

10 The object of our invention is to provide an improved amalgamator for treating gold and silver ores.

The invention consists of the combination, with a suitable tank or trough lined with 15 amalgamated copper plates and provided with a longitudinal groove in its bottom terminating in a well and a revoluble shaft fixed in the longitudinal axis of said tank and provided with angularly and radially adjustable 20 blades or screw-threads, preferably of amalgamated copper, of a series of amalgamated copper arresting-plates coated with quicksilver, vertically adjustable and removable, 25 suspended transversely within said tank and reaching from above the water-line nearly to the bottom of the tank, and it also embraces an inclosed amalgamated apron-plate connected with the discharge end of said tank and a mercury-trap set at the lower end of 30 said apron-plate to receive the discharge therefrom, and of certain other novel devices, all of which will be hereinafter described.

Reference is to be had to the accompanying 35 drawings, forming part of the specification, in which similar numerals of reference indicate corresponding parts in all the figures.

Figure 1 is a sectional side elevation of the amalgamating-tank and attachments. Fig. 2 40 is a vertical section of same on line X X, Fig. 1. Fig. 3 is an end elevation of the tank. Fig. 4 is a plan view on line Y Y, Fig. 1, with the arresting-plates removed. Fig. 5 is a reduced elevation of an arresting-plate. Fig. 45 6 is an end elevation of the same.

In the drawings, 1 represents the tank, having an inside rounded bottom 2 and upward-sloping sides 3, and having in its bottom a longitudinal groove 4 for the reception of the 50 excess of quicksilver, terminating at one end in a well 5, from which the amalgam and

fouled quicksilver, should there be any, may be removed when desired by a siphon or other suitable device. The tank is lined throughout with amalgamated copper plate, 55 as indicated at 6. The shaft 7, which has bearings designed to be water-tight in each end of the tank, has its outer end supported by standards 8, and is designed to be revolved in either direction by one or the other of its 60 pulleys 9. This shaft, within the tank, may be provided with a spiral screw-thread of sufficient width or depth to reach within an inch or thereabout of the bottom of the tank and about the same distance above the water-line, 65 as indicated at 10, but preferably it is provided with a series of blades 11, arranged in a double spiral and fixed in position by having their shanks passed through the shaft and held by nuts 12, as best shown in Fig. 1. These 70 blades may be made of any material sufficiently strong to keep the pulp in agitation, but preferably are made of flat plates of amalgamated copper, which will not only keep the pulp in agitation, but will also serve to catch 75 all the floating particles of gold with which they may make contact. They may be adjustably attached to the shaft in other ways than herein shown and described, but we prefer this method, as it enables the operator to 80 more readily remove, scrape, and replace them when "cleaning up." They may be set and firmly held with their faces at any desired angles to the shaft-axis and radially adjusted toward and from the shaft by means of the 85 nuts 12, and they may be made of various shapes, but we prefer them flat, as indicated.

In working a very "slimy" ore it is found best to radially adjust the blades to reach well above the water, so that they will when 90 in motion draw the "slimes" beneath the water and create deeper vortices, with the effect of forcing them in contact with amalgamated surfaces; and by angular adjustment of the blades the rate of the movement of 95 the ore-pulp from one end to the other of the amalgamator may be regulated, while by turning some of the blades at opposite angles to others a greater agitation of the pulp is effected.

In order to assure the arrest and amalgamation of all the particles of float-gold, to

present an increased amalgamating-surface within the limits of the tank, and to cause the pulp to be longer retained and more repeatedly exposed to the amalgamated surfaces, we suspend in the tank a series of amalgamated copper arresting-plates 13 coated with quicksilver, the lower half-circular edges of which are designed to reach considerably below the water-line and between the screw-blades, while their sides or legs extend below the screw-shaft at the sides thereof, and their upper edges are secured in strips 14 of wood or metal, as indicated in Figs. 1 and 2, which stiffen them and prevent their bending under the pressure of the moving water, and by means of which they may be removably clamped or otherwise secured to the upper edges of the tank, as indicated at 15, and be firmly held in position when adjusted. It will be seen that these arresting-plates are so constructed and arranged that the ore-pulp and water cannot flow over them and must flow beneath them through the annular spaces formed between them, the screw-shaft, and tank-bottom, and that in this respect—in their construction, their positions, and functions—they are entirely unlike the "rifles" or arresting-plates in common use.

The discharge end of the tank is provided with a series of narrow horizontal openings 16 at different levels, through which the water and pulp are designed to be discharged upon the apron-plate 17, which is covered with amalgamated copper and partially inclosed by side and front plates 18 and 19, respectively, to prevent the loss of the water and pulp by spattering. These discharge-openings 16 may be closed by eccentric-bars 20, as indicated at 21, Figs. 1 and 3, which bars are journaled, as shown at 22, on the discharge end of the tank, and they may be opened by the upward turning of said bars, as indicated. We do not confine ourselves to these special devices for regulating the discharge of the ore-pulp and water from the tank, as other devices quite as serviceable for the purpose may be applied without departing from our invention.

The ore-pulp and water discharged from the tank upon the apron-plate 17 may contain some particles of floured quicksilver and amalgam. Hence they are made to flow into the mercury-trap 23, which is designed to extend the whole width of the apron-plate and is provided with partition-plates 24, under and over which, respectively, the water and pulp flow in passing to the waste-sluice 25. In this mercury-trap the floured quicksilver and amalgam will sink to the bottom, from whence it may be easily removed in cleaning up; and water may be made to continually flow into the bottom of said trap through pipe 26 to prevent the pulp from settling therein.

In operating this amalgamator the amalgamating-surfaces are first properly prepared, and a quantity of quicksilver is then put into the groove 4 for the purpose of arresting and

amalgamating the heavier particles of gold that will sink to the bottom. All the openings in the discharge end of the tank are then closed and the ore-pulp with water is introduced into the upper or feed end until the water reaches nearly to the tips of the upward-projecting shaft paddles or blades. Then the shaft is alternately rotated in one direction and the other in order to bring all the particles of the metal in repeated contact with the amalgamated tank-lining, screw-blades, and arresting-plates. Then the upper discharge-opening is opened for the escape of water and pulp, and the shaft is kept revolving to cause the tank contents to flow in that direction, and a constant feed of ore-pulp and water into the tank is continued until the operation is suspended for the purpose of cleaning up. Then the discharge-openings, from above downward, are successively opened to permit the remaining water and pulp to discharge upon the apron-plate, and thence into the mercury-trap, and finally off through the waste-sluice 25. After the water and pulp have been discharged from the tank the excess of quicksilver charged with gold is siphoned or otherwise removed from the well 5, and the amalgamated surfaces are cleaned of their adhering coating of amalgam. For this purpose the arresting-plates and shaft-blades can readily be taken out, and the shaft may be removed, if necessary, and after the mercury-trap has been freed from pulp by proper flushing its contents of arrested floured quicksilver and amalgam are removed.

Though the shaft-blades in combination with the tank-lining present, in a given space, a much more extended amalgamated surface than is found in any other form of amalgamator of equal capacity, they would not be fully effective were it not for the amalgamated arresting-plates, which prevent the otherwise uninterrupted flow of the water and pulp from the feed end to and out of the discharge end of the tank, and which, each in its turn, impedes the flow of the water and pulp and causes them to swash and eddy against their amalgamated faces and to be forced down in repeated and frequent contact with the amalgamated shaft-blades and tank sides, so that the tank contents are constantly agitated and forced into repeated collision with amalgamated surfaces by a combination of forward-and-backward, of right-and-left rotary, up-and-down vertical, vertical, and lateral movements from one side to the other, whereby every particle of amalgamable gold must be arrested and amalgamated.

Though the extended amalgamated surfaces of the tank-lining and shaft-blades and the quicksilver in the groove will readily catch and retain all of the heavier particles of the metals that are in a condition to be amalgamated and that are deflected against them by the arresting-plates, it is the arresting-plates themselves that, coated with quicksilver, serve

most effectually to catch and amalgamate the float-gold, which in some ores constitute their greatest values and most of which otherwise would be lost.

Having thus described our invention, we claim as new and desire to secure by Letters Patent—

1. An amalgamator constructed substantially as herein shown and described, consisting of a tank lined with amalgamated plates, a shaft made to revolve in the longitudinal axis thereof, and carrying amalgamated blades adapted for radial and angular adjustment, preferably arranged in spirals, and a series of vertically-adjustable, removable, amalgamated, arresting-plates extending above the water-line and having a space beneath their lower edges for the flow of the water and ore-pulp, all arranged and operated substantially as set forth.

2. The combination with an amalgamator consisting of a tank lined with amalgamated plates and having a longitudinal groove and well in its bottom and a series of adjustable

discharge - openings at one end, provided with a revoluble shaft carrying amalgamated blades, and with a series of vertically-adjustable amalgamated arresting-plates, of an enclosed amalgamated apron-plate fixed at the discharge end of the tank, and of a mercury-trap set to receive the material discharged from the said apron-plate, all arranged and operated as herein shown and described.

3. The combination with an amalgamating-tank constructed substantially as herein shown and described, of a revoluble shaft fixed in the longitudinal axis thereof, and provided with angularly and radially adjustable amalgamated copper blades, as set forth.

In testimony that we claim the foregoing we have hereunto set our hands, in the presence of two witnesses, this 8th day of May, 1893.

JACOB J. STORER.
FRANK MARTIN.
